UNITED STATES PATENT OFFICE.

WILLIAM A. REED, OF CHELSEA, MASSACHUSETTS, ASSIGNOR TO UNITED SHOE MACHINERY COMPANY, OF PATERSON, NEW JERSEY, A CORPORATION OF NEW JERSEY.

ABRADING-MACHINE.

1,167,521.

Specification of Letters Patent.

Patented Jan. 11, 1916.

Application filed June 26, 1911. Serial No. 635,446.

To all whom it may concern:

Be it known that I, WILLIAM A. REED, a citizen of the United States, residing at Chelsea, in the county of Suffolk and State of Massachusetts, have invented certain Improvements in Abrading-Machines, of which the following description, in connection with the accompanying drawing, is a specification, like reference characters on the drawings indicating like parts in the several figures.

This invention relates to abrading and similar machines the waste product of which consists in whole or in part of small particles which are carried away by an exhaust current, and is herein illustrated as embodied in a machine for buffing the bottoms of boots and shoes.

The general object of the invention is to conserve and concentrate the force of the draft and to apply it solely to the tool or tools which are actually operating upon the work.

To this end one feature of the invention consists in a machine having an operating tool and an exhaust pipe arranged to withdraw waste material caused by the action of said tool upon the work, of means normally closing the exhaust pipe while no work is being operated upon, and means arranged for convenient actuation upon presentation of a piece of work to said tool for opening said closing means.

In the illustrative machine, the closing means takes the form of a valve which is opened by the pressure of the work against an actuating member and the consequent moving of said member. Under these circumstances it is desirable that a slight movement only of the valve-actuating member should be required; and accordingly, another feature of the invention consists in a machine of the class described of a valve for controlling the exhaust current, means operated by the presentation of the work for partially opening said valve, and means operated by the exhaust current for thereafter completing the opening movement. And preferably the last-named means takes the form of a second valve located in a branch pipe so that the opening of one valve closes the other.

The illustrative machine is shown as provided with a plurality of operating tools from which separate passages or branches lead to the exhaust pipe, said machine being

designed for the use of a single operator who presents the work selectively to one tool or another. Since only one tool is operating upon the work at any given moment it is desirable that the whole force of the exhaust current be applied to that tool.

Accordingly, another feature of the invention consists in a machine having a plurality of operating tools, of an exhaust pipe and passages leading from said tools to said pipe, of valves for controlling said passages and means for simultaneously opening one valve and closing another. And preferably, as illustrated, this means is actuated by the presentation of the work in position to be operated upon.

These and other features of the invention including certain details of construction and combinations of parts will be set forth in connection with an illustrative machine and will be pointed out in the appended claims.

Referring now to the accompanying drawings:—Figure 1 is a plan of a portion of a machine for buffing boots and shoes in which the present invention is embodied; Fig. 2 is a side elevation of a portion of the machine; Fig. 3 is a detail showing the mounting of the valves or dampers; and Fig. 4 is a perspective showing the lining of the hood together with the valves and their actuating mechanism.

Referring more particularly to Figs. 1 and 2, the buffing rolls 1 and 3 are fast to a shaft 5 which is adapted to be rotated by a pulley 7 and belt 8 and to be longitudinally reciprocated by a bell-crank lever 9 and a rod 11, said rod and belt being operatively connected with the usual counter-shaft, not shown. The rolls are partially inclosed in the usual manner by a casting 13 and a plate 15, and from the rear end an exhaust pipe 17 leads to a main exhaust pipe, in case the factory is fitted with a blower system, or to an exhaust fan which is commonly driven from the counter-shaft of the machine. As thus far described the machine is of a well-known, commercial type; and the details of its construction will not be further set forth, since the invention is applicable generally to machines in which a current of air removes the waste material caused by the action of the tool upon the work.

Located within the casting which partially incloses the roll is a lining 19 of suitable sheet material, said lining being ap-

proximately funnel-shaped and terminating in an outlet 21 which fits within the exhaust pipe 17. Extending medially of this lining 19 is a partition 23 which thus forms two 5 passages each leading from one of the rolls to the exhaust pipe, and at the inner end of said partition is located an upright spindle 25 which is rotatably mounted in the casting 13. This spindle has upon its lower end 10 an enlarged portion 27 and a gear 29, and its upper end projects through a washer 31 and receives a cotter pin 33 by which it is held in place. The body portion of the spindle is rectangular in cross section, and 15 to it is clamped, by means of a bent plate 35, a sheet of metal forming two valves 37 and 39. As will be seen by reference to Fig. 4 one of these valves is normally in closed position with a large surface exposed to the 20 action of the exhaust current so that it is held thereby in the position shown, while the other valve is normally in open position and extends approximately in the direction in which the exhaust current is moving so 25 that a small surface is exposed to the action of said current. Thus, owing to the relative position of the parts, the force of the exhaust current is exerted entirely upon one valve and tends to hold that valve closed and 30 to hold the other valve against the partition 23 which serves in this connection as a stop. It should also be observed that as the valve 37 is swung to the left an increasing extent of it will be exposed to the action of 35 the exhaust current while a decreasing extent of the valve 39 will be so exposed until a point is reached where the exhaust current will operate to close the valve 37 and open the valve 39. If now the valve 39 is 40 moved toward its closed position exactly the reverse conditions will be produced so that the closing movements of the valves are automatically effected by the exhaust current.

In order to provide means for partially 45 opening and closing the valves a gear 34 which meshes with the gear 29 is angularly movable about the pivot 36, and to this gear there is fastened, by means of pins 38, a lever 41 which may be actuated in any suitable manner.

In the illustrative machine the presentation 50 of a piece of work to one of the rolls operates to direct the draft entirely upon that roll, and to this end contact members 43 and 45 are provided in the form of felt disks which are clamped fast to said lever by bolts 47, the upper ends of which are screw threaded to receive flat nuts 49. The 55 purpose of this method of fastening the disks in position is to permit them to be turned so as to expose a new portion to the work when the old portion has become worn. These members 43 and 45 are arranged in the illustrated machine below the buffering 60 rolls in the path of presentation of the shoe 65

so that, as the operator presents a shoe to the under surface of a roll, the valve or damper which controls the draft upon that roll is automatically opened and the other valve or damper closed. It will be obvious 70 that the contact member may be moved to its extreme inner position by the shoe if desired, but that it is necessary merely to move it part way whereupon the exhaust current will operate to complete the opening movement of the valve and at the same time move the contact member to its extreme inner position in which it will not interfere with the proper presentation of a shoe to the buffering roll.

Although the invention has been set forth in connection with a buffering machine in which a valve is automatically actuated by presenting a shoe to the machine, it should be understood that the invention is limited 85 in the scope of its application neither to the particular machine shown and described nor to the automatic actuation of the valve.

Having thus described my invention, what I claim and desire to secure by Letters Patent of the United States is:—

1. A machine of the class described having an operating tool and an exhaust pipe arranged to withdraw waste material caused by the operation of said tool in combination with a valve for controlling said pipe, means for partially opening said valve, and a member of sufficient area when acted upon by the exhaust current to enable it to acuate the valve and movable with said valve into the path of the exhaust current whereby the action of said current upon said member completes the opening of said valve.

2. A machine of the class described having a plurality of operating tools, an exhaust pipe, and passages leading from said tools to said pipe, in combination with valves for closing said passages, and a member movable to open and close said valves, said member being located to be engaged by the work as it is presented to the operating tools.

3. A machine of the class described having two operating tools, an exhaust pipe through which a current of air is drawn, and passages leading from said tools to said pipe, in combination with valves one of which normally extends across one of the passages while the other extends approximately in the direction of the exhaust current, and means for moving said valves angularly to a position in which the exhaust current will tend to reverse the effective positions of the valves.

4. A machine of the class described having two tools, an exhaust pipe through which a current of air is drawn, a hood partially inclosing said tools, said hood being divided by a partition to form a separate passage leading from each tool to the exhaust pipe, two valves rigidly connected,

- arranged at an angle to each other and angularly movable about an axis located in the plane of the partition, one valve being normally held in closed position and the other in 5 open position against the partition by the exhaust current, and means operated by presentation of a piece of work to one of the tools for moving said valves to a position in which the current will act to close the valve 10 which was previously open and to hold open the valve which was previously closed.
5. A machine of the class described having two tools, an exhaust pipe through which a current of air is drawn, said pipe 15 having forks leading to said tools, and two valves arranged at an angle to each other the angular relation of said valves to each other and to the forks being such that when one valve is closed the other presents its 20 surface of smallest dimension to the action of the exhaust current.
6. A machine of the class described having a plurality of operating tools, an exhaust pipe, and passages leading from said tools 25 to said pipe, in combination with valves for controlling said passages, and actuating members for said valves arranged in the path of presentation of the work to said tools.
7. A machine of the class described having a plurality of operating tools, an exhaust pipe, and passages leading from said tools to said pipe, in combination with valves for controlling said passages, a spindle upon 35 which said valves are mounted, a gear fast to said spindle, and means for moving said gear angularly arranged to be engaged by the work as it is presented in position to be operated upon by one of said tools.
8. A buffing machine for boots and shoes 40 having two buffing rolls, an exhaust pipe, and passages leading from said rolls to said pipe, in combination with valves for controlling said passages, a spindle upon which said valves are mounted at an angle to each 45 other and actuating means for said valves arranged to be engaged by the shoe as it is presented to be buffed for simultaneously operating the valves to close one passage and open the other.
- 50 9. A machine of the class described hav-
- ing, in combination, two operating tools, an exhaust pipe having branches leading to said tools, valves for controlling said branches, a pivot for said valves located at the junction of said branches, said valves being arranged 55 at an angle to each other and being arranged each to swing forward toward its corresponding operating tool to open the branch which it controls.
10. A machine of the class described having, in combination, an operating tool, an exhaust pipe through which a draft is produced to remove dust generated by the operation of said tool, said pipe having two branches, one of which leads to said tool, 60 two valves for controlling said branches, said valves being arranged at an angle to each other and angularly movable in unison about a common axis whereby the area presented by one to the draft is increased as 65 that of the other is diminished.
11. A machine of the class described having, an operating tool and an exhaust pipe arranged to withdraw waste material caused by the operation of said tool in combination 70 with a valve for controlling said pipe, a movable member operated by presentation of the work for partially opening said valve, and a member having an actuating connection with said movable member and of sufficient area to be operated by the exhaust current for thereafter completing the opening movement.
12. A machine of the class described having, in combination, a plurality of operating 75 tools, separate passages leading from each tool to an exhaust pipe, and means located in the path of presentation of the work to the tools and adapted to be operated upon presentation of a piece of work to any selected tool for concentrating the whole draft upon that tool.

In testimony whereof I have signed my name to this specification in the presence of two subscribing witnesses.

WILLIAM A. REED.
